ARRANGEMENT FOR VARIABLE ADJUSTMENT OF BAND WIDTH

Johannes Winkler, Berlin, Germany, assignor to
 Telefunken Gesellschaft für Drahtlose Tele-
 graphie m. b. H., Berlin, Germany, a corpora-
 tion of Germany

Application November 20, 1937, Serial No. 175,593
 In Germany December 21, 1936

5 Claims. (Cl. 178—44)

It is known that a bandpass filter of two resonant circuits coupled together can be made variable by changing the inductive coupling. When a change of the coupling is attempted in practice through the moving of one of the coils a serious difficulty is encountered as soon as the bandpass filter coils are placed under a shield. The tilting of one coil about its axis with respect to that of the other changes the position of the tilted coil with respect to also the shield and the tuning becomes disturbed. This same holds true when one of the coils is moved up or down along their common axis. In this latter case the distance between the movable coil and a part of the shield is changed.

An attempt has been made to overcome this difficulty by the construction of two telescoping can-shaped shielding members in which the coils were placed. For a change in the inductive coupling the coils are moved together with their respective shields along their common axis. This arrangement is naturally very clumsy and in the case of iron-cored coils it has the added disadvantage that the tuning becomes disturbed as soon as the distance between the iron cores is changed.

Pursuant to the invention another known method of changing the coupling is employed in a hereinafter described manner. This method of changing the coupling is realized by moving back and forth along the common axis of the main coils of the two resonant circuits, a smaller coil placed between the two coils and connected in series with the main coil of one of the resonant circuits. The innovation lies in the fact, that by this method of band width adjustment the main coil and the small coupling coil of one resonant circuit and the coil of the other resonant circuit, mounted side by side along a common axis can be placed under a single shield and that the small coupling coil placed between the two other coils can be moved back and forth along the common coil axis.

In the drawing Figure 1 illustrates one example of constructional arrangement pursuant to the invention, Figure 2 is a diagrammatical representation or circuit diagram of the embodiment disclosed in Figure 1, and in Figure 3 are shown selectivity or resonance curves obtained with the embodiment disclosed in Figures 1 and 2. In Figures 1 and 2 the coils are designated by the same reference numbers. In Figure 1, under the shield can A is the tube R made of insulating material which serves for the permanent mounting of coils L₁ and L₂. The members shown in

10 dotted line are the iron cores, the position of which is adjustable through openings in the shield (not shown) for tuning in a manner well known. These cores are ferromagnetic and consist of finely divided individually insulated magnetic particles compressed with a binding material and moulded under pressure to make a core body. Coil L₂ is mounted on a sliding sleeve of somewhat greater diameter than the mounting tube and by means of lever H and rod S can be moved up or down. Since L₂ only has to have approximately $\frac{1}{300}$ part of the self inductance of coil L₁ the tuning is practically unaffected especially when the position of the iron cores is such, that 15 on the side facing each other, they do not protrude beyond the ends of their respective coils.

A further essential advantage of the invention resides in the fact that the sliding movement of a small coil requires less constructional expense than if the main coils were made movable, especially when they have iron cores.

In Figure 3 there are shown the selectivity curves for the narrow and wide band adjustments of the circuit. Adjustment of the small coil L₂ towards the fixed coil L₃ will produce close coupling between the two coupled circuits and the selectivity curve for that condition will be the substantially flat topped curve of Figure 3, whereas adjustment of the small movable coil L₂ in the direction away from the coil L₃ will produce a loose coupling between the coupled circuits and the selectivity curve for that condition of adjustment will be substantially sharp and narrow. In a trial experiment, for a bandpass filter tuned to an intermediate frequency of 490 kc./s. the coil L₁ had 180 windings, L₂ 15 windings and L₃ 170 windings. The winding ratio of L₂ to L₁ therefore is 1:12 giving an inductance ratio of 1:144 in the case of aircores. Since the example illustrated herein relates to iron cores, the ratio is 20 greater than 1:300.

This bandpass filter is primarily intended for the intermediate frequency portion of a receiver, although it is fundamentally applicable to the received frequencies as well. The variable coupling can also be combined in a known manner, for instance, for simultaneous control adjustment with the tuning or else it can be made adjustable by hand.

50 What I claim is:

1. The combination with a pair of tuned circuits having main reactances coaxially disposed in fixed spaced relation, of means for varying the coefficient of coupling between said reactances, said means comprising an auxiliary inductance

coaxially arranged between the main reactances, said auxiliary inductance being disposed closer to one of the reactances than to the other and being serially connected to said other reactance, a shielding can enclosing the reactances and the auxiliary inductance, and means for adjusting the position of the auxiliary inductance from outside the shielding can.

2. The combination with a pair of tuned circuits having main inductances which are coaxially disposed in fixed spaced relation, of means for varying the coefficient of coupling between said inductances, said means comprising an axially adjustable auxiliary inductance connected in circuit with one of said main inductances and in inductively coupled relation with the other of said inductances, a shielding can enclosing all of said inductances, means arranged externally of the shielding can for adjusting the axial position of said auxiliary inductance and thereby to vary said inductive coupling.

3. The combination with a pair of tuned circuits having a pair of main inductances coaxially disposed on a common support and in coupled relation, of a shield can enclosing said inductances, said shield having a disturbing effect on the tuning of said circuits with variation of

the coupling by coaxial movement of the inductances, means for avoiding said disturbing effect with change of coupling comprising a small auxiliary coil adjustably mounted on said support and disposed between the main inductances which are maintained in fixed position, said auxiliary coil being in inductively coupled relation with one of the inductances and serially connected in circuit with the other of said inductances, and means 10 extending from the auxiliary coil through the shield can whereby the coupling between the circuits may be varied.

4. A bandpass filter comprising a pair of coupled tunable circuits, the coils of which are coaxially mounted in fixed relation within a common shielding can, the coil of one of said circuits having in series with it a smaller coil which is also coaxially mounted and closer to the coil of the other circuit, said smaller coil being adapted for axial adjustment to vary the band width without disturbing the tuning, and means arranged externally of the shielding can for making said adjustment.

5. A bandpass filter according to claim 4, 15 wherein adjustable iron cores are associated with the fixed coils to vary the tuning of the circuits.

JOHANNES WINKLER.
